UNITED STATES PATENT OFFICE.

FLOYD K. EASTMAN, OF KOKOMO, INDIANA, ASSIGNOR TO CONCEALED DOOR CHECK COMPANY, OF KOKOMO, INDIANA, A CORPORATION.

DOORCHECK.

Application filed May 15, 1924. Serial No. 713,445.

To all whom it may concern:

Be it known that I, FLOYD K. EASTMAN, a citizen of the United States, and a resident of Kokomo, county of Howard, and State of

5 Indiana, have invented a certain new and useful Doorcheck; and I do hereby declare that the following is a full, clear, and exact description thereof, reference being had to the accompanying drawings, in which like 10 numerals refer to like parts.

This invention pertains to a door check adapted particularly for use in connection with vehicle doors or the like.

15 The object of the invention is to provide a simple and economically manufactured metallic door check having a spring bumper associated therewith for taking up shock.

20 The principal feature of the invention resides in the arrangement of a metallic strap in conjunction with the holding plates and spring bumper, wherein the check may be readily attached to the door and frame as an accessory, or may be built into the frame as standard equipment.

25 A further feature of the invention resides in the construction of a wire strap, which, in connection with the other parts provides an efficient but economical device of this character.

30 The full nature of the invention will be understood from the accompanying drawings and the following descriptions and claims:

35 Fig. 1 is a plan view of the check mounted on the door, with the door in closed position. Fig. 2 is a section taken on the line 2—2 of Fig. 1. Fig. 3 is the same as Fig. 2 showing the door in open position.

40 In the drawings there is shown a door pillar 10 forming a part of the door 11, which is hinged by means of the hinge 12 to the body pillar 13 forming a part of the body 14, the door and body pillars being so arranged as to lie adjacent each other when the 45 door is in closed position, and swing a substantial distance away from each other when the door is open by reason of the elongated hinge 12.

45 Rigidly secured to the inner face of each 50 of the door pillars there is a stop plate 15 having a flange 16 extending inwardly adjacent the inner surface of the pillar, the same being in the form of the usual angle plate. Said plate is rigidly secured to the

door pillar by a central screw 17 extending 55 into the center of the laterally formed groove 18 cut into the adjacent surface of the pillar.

On the body pillar, in alignment with the plate 15, there is a check plate 19 in the 60 form of an angle plate having a flange 20 extending adjacent the inner surface of said pillar. The check plate is rigidly secured to the body pillar by means of the screws 21 extending into the pillar on each side of the 65 laterally extending groove 22.

Connecting the plates 15 and 19 there is a metallic strap of a resilient nature, which, as herein shown, is formed of a wire 23 bent intermediate its ends at 24, and further having its ends bent back on each other forming loops 25. The free ends of the wire are bent at right angles to provide the hooks 26.

A bumper is provided by mounting the spiral spring 27 over the looped end 24 of 75 the wire and sliding it longitudinally thereof so that it surrounds the shank portion of the wire and abuts against the looped ends 25, said spring being embraced by the looped portions of the wire 28. The wire strap is 80 then laid in the grooves 18 and 22, with the door in closed position and the plates 15 and 19 are then secured thereover so as to slidably maintain the wire strap in said grooves. The screw 17 is caused to be straddled by the 85 wire so that when the door is in open position as shown in Fig. 3 the end 24 thereof will engage the screw as a stop. The free ends 26 of the wire are arranged to project outwardly for engaging the forward edge 90 of the check plate 19, and are held thereagainst under spring tension by the spring 27 which abuts the body pillar 13.

It will be observed that the parts forming the structure are of a simple character, 95 comprising only the bent wire strap, the two metal plates 15 and 19 which may be readily stamped out, the spring 27, and the screws. Furthermore it is readily assembled as above described.

100 For protecting the edge of the body pillar against which the strap will be drawn when the door is opened, there is provided a fibre friction plate 29 over which the strap is drawn upon the door being opened. It will 105 be obvious that the strap may be readily mounted on the door structure during the manufacture of the vehicle body, and as an

accessory the immediate upholstering may be loosened, the recesses 18 and 22 cut in the pillars, the plates secured in place with the metal strap inserted under the upholstering. 5 Furthermore it will be observed that the metal strap is of such resilience as to permit it to be bent as shown in Fig. 3 and immediately thereafter upon closing the door, straighten up to substantially the position 10 shown in Fig. 2 so as not to interfere with the upholstering or the lowering of the door window.

The invention claimed is:

1. The combination with a body pillar 15 and a door pillar hinged thereto, of a door check comprising a resilient wire member slidably mounted on the outside thereof, plates secured to the exterior surface of said pillars for supporting said wire member in 20 slidable relation thereto, and a resilient cushion member, said wire being bent intermediate its ends to provide a stop loop for limiting its relative movement with respect to one of said plates, and bent at its free 25 ends for receiving and maintaining the said cushion member in position against the other plate for absorbing the shock occasioned by the movement of the door pillar to its extreme position.
- 30 2. The combination with a body pillar and a door pillar hinged thereto, said pillars being provided with aligned grooves in the exterior surface thereof, of a door check comprising plates secured over said grooves, 35 and a resilient wire strap slidably mounted in said grooves on the exterior surface of said pillars and held therein by said plates, said wire being bent U-shape intermediate its ends so as to provide two shank portions, 40 the free ends of the wire being looped back upon themselves for receiving and holding a cushion member in said looped portion, the loops of said wire providing means for lim-

iting the opening movement of the door pillar.

3. The combination of a body pillar and a door pillar hinged thereto, said pillars having aligned grooves therein, of a door check comprising plates secured to each of said pillars over said grooves, a resilient metal wire looped intermediate its ends to provide two shank portions, the free ends of said wire being looped back upon themselves, and provided with hooked ends for engaging one of said plates, means in the 55 other plate extending between the shank portion of said wire adapted to be engaged by the loop thereof formed intermediate its ends, and a compression spring mounted about the shank portion of said wire and 60 embraced by the looped ends thereof adapted to be compressed between said looped ends and the adjacent plate, substantially as and for the purpose described.

4. The combination of the body pillar and a door pillar hinged thereto, of a door check comprising a plate member secured to each of said pillars, a resilient wire strap slidably held in place by said plate members, said strap having a loop formed therein so as to 70 provide two shank portions extending in spaced relation with each other, means on one of said plate members extending between said shank portions adapted to be engaged by the loop formed thereby for limiting the sliding movement of said strap, the free ends of said strap being looped back upon each other and provided with hooked ends adapted to engage the other plate member, and a compression spring seated in said 80 last mentioned looped ends to bear against the adjacent plate member, substantially as and for the purpose described.

In witness whereof, I have hereunto affixed my signature.

FLOYD K. EASTMAN.
